UNITED STATES PATENT OFFICE.

JOHN T. HYNDMAN, OF CINCINNATI, OHIO, ASSIGNOR TO WM. G. HYNDMAN AND ROBERT J. HYNDMAN, OF SAME PLACE.

METALLIC SHINGLE.

SPECIFICATION forming part of Letters Patent No. 326,655, dated September 22, 1885.

Application filed July 16, 1885. (No model.)

To all whom it may concern:

Be it known that I JOHN T. HYNDMAN, a citizen of the United States residing at Cincinnati, in the county of Hamilton and State 5 of Ohio, have invented certain new and useful Improvements in Metallic Shingles; and I do hereby declare that the following is a full, clear, and exact description of the same, reference being had to the annexed drawings, 10 making a part of this specification, and to the letters and figures of reference marked thereon.

Figure 1 of the drawings is a perspective view showing the manner of connecting the shingles together; Fig. 2, a perspective view of one of the shingles, and Fig. 3 a sectional view thereof taken on line xx of Fig. 2.

The present invention has relation to certain new and useful improvements in metallic roofing-shingles; and the object thereof is to 20 so construct the shingles as to enable them to be quickly and securely connected together.

The invention therefore consists in forming a scroll or coil along the shingle, at or near the center thereof, of such shape that when sprung over the scroll or coil of the shingle below it 25 will by its tendency to contract firmly embrace and clamp itself around the under scroll or coil, as will be hereinafter described and 30 claimed.

In the accompanying drawings, A represents the shingle constructed of sheet metal and of any style and shape as found desirable.

The shingle A is formed with a central scroll or coil, a , which is greater than a semicircle 35 in cross-section, as shown in Fig. 3, thus rendering it necessary to expand when engaging with the scroll or coil of the shingle below it, and the natural tendency to contract in regaining its normal shape will of itself firmly 40 embrace and clamp the shingle to the one below it, thus enabling the entire number of shingles on a roof or other structure to be effectually secured together, the body of the shingles being secured to the roof by nailing. 45 One end of the scroll or coil a may be made a little larger, so as to be more easily slipped over the scroll or coil of the adjacent shingle, thus completely covering the nail-heads of the shingle below it.

Having now fully described my invention, what I claim as new, and desire to secure by Letters Patent, is—

A metallic roofing-shingle formed with a scroll or coil of a size greater than a semicircle, 55 whereby it will act as a spring clamp upon the scroll or coil of the shingle below it to fasten itself thereto, substantially as and for the purpose set forth.

In testimony that I claim the above I have 60 hereunto subscribed my name in the presence of two witnesses.

JOHN T. HYNDMAN.
